FAMILY ALTAR

William H. Banck, 6819 8th St. NW, Washington, D.C.

Filed Sept. 17, 1962, Ser. No. 71,734

Term of patent 14 years

(Cl. D29—23)

The essential features of my design reside in the portions shown in full lines.

I claim:

The ornamental design for a family altar substantially as shown and described.
